(57) **CLAIM**

The ornamental design for a stackable shoe rack, as shown and described.

DESCRIPTION

FIG. 1 is a front, left side perspective view of a stackable shoe rack showing my new design with parts of adjacent, identical shoe racks in a stack of such shoe racks being shown in phantom lines for the purpose of showing the stackability of the shoe racks and forming no part of the claimed design, shoes being placed on the elongate members extending between the end parts;

FIG. 2 is a front elevational view thereof;

FIG. 3 is a right side elevational view thereof with parts of adjacent, identical shoe racks in a stack of such shoe racks being shown in phantom lines for the purpose of showing the stackability of the shoe racks, and forming no part of the claimed design;

FIG. 4 is a left side elevational view thereof with parts of adjacent, identical shoe racks in a stack of such shoe racks being shown in phantom lines for the purpose of showing the stackability of the shoe racks, and forming no part of the claimed design;

FIG. 5 is a rear elevational view thereof;

FIG. 6 is a top plan view thereof; and,

FIG. 7 is a bottom plan view thereof.
